Primary Examiner — Mitchell I. Siegel

(74) Attorney, Agent, or Firm — Norris McLaughlin, P.A.

(57) **CLAIM**

The original design for a climbing structure, as shown and described.

DESCRIPTION

FIG. 1 is a perspective view of our climbing structure;
FIG. 2 is a top plan view;
FIG. 3 is a front elevational view; and,
FIG. 4 is a side elevational view.

1 Claim, 4 Drawing Sheets(56)
